(57) CLAIM

The ornamental design for a bottle, as shown and described.

DESCRIPTION

FIG. 1 is a front perspective view of a bottle showing my new design;

FIG. 2 is a front view of the bottle shown in FIG. 1 (with the rear and side views being the same);

FIG. 3 is a top view of the bottle shown in FIG. 1; and,

FIG. 4 is a bottom view of the bottle shown in FIG. 1.

The broken line depicting a portion of the bottle top, and bottom recessed portion, shows unclaimed subject matter.
